UNITED STATES PATENT OFFICE.

JOSEPH TAMS, OF TRENTON, NEW JERSEY.

BUTTON.

949,310.

Specification of Letters Patent. Patented Feb. 15, 1910.

Application filed December 31, 1898. Serial No. 470,163.

To all whom it may concern:

Be it known that I, JOSEPH TAMS, a citizen of the United States, residing at Trenton, in the county of Mercer and State of New Jersey, have invented a new and useful Button, of which the following is a specification.

This invention relates to detachable buttons, and more particularly to that class of buttons in which novel means are provided 10 that will permit of the same to be readily applied and securely retained on any fabric.

While this device is especially designed for use on clothing generally, it is also applicable for use in other arts, wherein a button 15 is employed and a removable fastening for the button is desired.

The object of the invention is to provide a button-head of any style, with a shank member having its free end terminating in a reversely turned and pointed hook which is 20 adapted to engage in the fabric and thereby prevent the button from becoming disengaged.

In the drawings—Figure 1 is a side elevation 25 of my invention, showing the same applied to a fabric, said fabric being shown in cross-section. Fig. 2 is a bottom plan view of the device, showing the same applied to a fabric, with the outer lining thereof removed. Fig. 3 is a bottom plan view of the device showing the same applied to a fabric with both linings removed. Fig. 4 is a bottom plan view of the device. Fig. 5 is a vertical sectional view of the device. Fig. 6 is 35 an inverted perspective view of the device, and Fig. 7 is a vertical sectional view showing a modified form of my invention.

Like numerals of reference designate corresponding parts in all the figures of the 40 drawings.

Referring to the drawings, 7 designates the head of a button of any desirable construction. Integral with and extending centrally from the back of the head, is a shank 8, around which is arranged a coiled spring wire 9. One end of this wire is firmly secured to the back 7^a of the button-head by solder or any other suitable means. The coils are preferably compressed together the 50 entire length of the shank 8, and are also arranged to closely embrace the said shank. The last coil 9^a of the wire is formed with a greater diameter than the others, and is also inclined a certain distance therefrom in 55 order to provide room for the entrance of a fabric. This coil extends a short distance

beyond the end 8^a of the shank, and, as shown in the accompanying drawings, includes a substantially right-angled bend 9^b. The free end of the looped spring wire 9 extends downwardly at an angle from the bend and terminates in an offset and reversely turned hook 10 which is provided with a fabric penetrating point 10^a, the outer arm 10^b of the hook being preferably curved so as to easily pierce a fabric. The hook 10 which extends from the last coil 9^a, is arranged at an obtuse angle with respect to the center line of the coiled body. This construction enables the operator to pierce a fabric with the hook without the necessity of turning the button to one side.

In applying this button, the point 10^a of the hook 10 is inserted into a fabric 13 and the button turned to the right until the last 75 coil 9^a of the spring wire comes into contact with the fabric. The button is then given a reverse turn to the left, which, by reason of the coiled wire, will cause the fabric 13 to be tightly compressed between the end 8^a, 80 of the shank and the last coil 9^a of the spring wire. The substantially right angled bend 9^b of said coil, will tend to prevent the button from turning. The button is again turned to the right and the hook is caused 85 to penetrate the lining 11 of the said fabric. Thus, it will be seen that the reversely turned hook will prevent the button from becoming accidentally detached.

As shown by reference to Fig. 1 of the 90 drawing, this button is especially applicable for use on clothes in which two linings are employed, the hook being designed to engage the inner or center lining 11, the outer lining 12 serving as a guard to protect other 95 fabric from contacting with the point of the hook.

The shank of the button may be formed entirely of the coiled wire and thus the shank 8 may be dispensed with. I wish it understood that in the claims the term "shank" includes either construction, unless the express language of the claims defines a different meaning.

From the foregoing, it is thought that the 105 construction, operation, and many advantages of the herein described invention will be apparent to those skilled in the art, without further description, and it will be understood that various changes in the size, 110 shape, proportion and minor details of construction may be resorted to without de-

parting from the spirit or sacrificing any of the advantages of the invention.

Having thus described my invention, what I claim as new and desire to secure by Letters-Patent is—

1. A detachable button comprising a head, a shank extending from the head, and a coiled member arranged around and tightly embracing the shank and having one end secured to the head, and the free end thereof terminating in a reversely turned hook.

2. A detachable button comprising a head, and a rigid shank member extending from the head and having a coiled wire body, the last coil of the body being spaced from the preceding one and extending beyond the shank, and a reversely turned hook extending from the last coil.

3. A detachable button comprising a head, a rigid shank member extending from the head and having a coiled wire body, the last coil of the body being spaced from the preceding one, said last coil including a substantially right angled bend, and a reversely turned hook extending from the last coil, said hook being arranged at an angle to the button head.

4. A detachable button comprising a head and a shank member having a coiled body, the outer coil extending from the shank and of greater diameter than the contiguous coil, said coil being inclined to provide space for a fabric to be received and clamped against the end of the shank member, and a hook extending from the said outer coil and offset from said coiled body.

5. A detachable button comprising a head, a rigid shank member having a coiled wire body provided with a clamping coil at its outer end for clamping the fabric between it and the adjacent coil of the body, and a hook extending outwardly from the coiled body and arranged at an obtuse angle with respect to the center line of the body, said hook being adapted to engage the fabric and thereby prevent the rotation and consequent displacement of the button.

6. A detachable button comprising a head, a rigid shank member provided with a clamp at its outer end for clamping the fabric between it and the adjacent end of the shank, and a hook extending outwardly from the shank member and arranged at an obtuse angle with respect to the center line thereof, the hook being reversely turned and the outer arm thereof being pointed and arranged in a lower plane than the inner arm.

7. A detachable button comprising a head, a rigid shank member, and a hook extending outwardly from the shank member and arranged at an obtuse angle with respect to the center line thereof, the hook being reversely turned and the outer arm thereof being pointed and arranged in a lower plane than the inner arm.

In testimony, that I claim the foregoing as my own, I have hereto affixed my signature in the presence of two witnesses.

JOSEPH TAMS.
